UNITED STATES PATENT OFFICE.

J WALTER MOORE, OF FORT EDWARD, NEW YORK.

MAGNETIC FLAT-IRON.

1,135,389.

Specification of Letters Patent. Patented Apr. 13, 1915.

Application filed September 23, 1913. Serial No. 791,429.

To all whom it may concern:

Be it known that I, J WALTER MOORE, citizen of the United States, residing at Fort Edward, in the county of Washington 5 and State of New York, have invented certain new and useful Improvements in Magnetic Flat-Irons, of which the following is a specification.

My invention relates to new and useful 10 improvements in flat irons and more particularly to irons employed for pressing heavy goods and garments, the object of my invention being to provide an iron which, although relatively light in construction, 15 may be made to exert practically any desired degree of pressure upon the garment without effort upon the part of the operator.

A further object of my invention is to 20 provide a flat iron including an electro-magnet in its construction, the flat iron being adapted for use in connection with a table or ironing board, either formed of iron or similar suitable metal which will be 25 attracted by the magnet or having a sheet or plate of such metal laid upon or inserted in the surface of the table or board.

A further object of my invention is to 30 provide a flat iron construction including an electro-magnet, the coils of the electro-magnet being so formed that they may also serve as heating coils to heat the iron and maintain the same at the proper temperature.

35 In this connection a still further object of my invention is to provide an electro-magnet the coils of which are so wound that by the proper manipulation of switches positioned in the handle the direction of current may be reversed through certain of 40 the coils to vary the attractive force of the magnet without varying its heating effect.

A still further object of my invention is 45 to provide a flat iron having an electro-magnet in its construction and also provided with separate and independent heating coils in order that the iron may be heated without energizing the electro-magnet if desired. And a still further object of my 50 invention is to provide means whereby the current may be shut off from either the heating coils or from the electro-magnet, said means being so arranged as to in no way interfere with the reversing of the direction of flow of current through certain

of the coils of the electro-magnet to vary its attractive powers.

With these and other objects in view, my invention will be more fully described, illustrated in the accompanying drawings and 60 then specifically pointed out in the claims which are attached to and form a part of this application.

In the accompanying drawings: Figure 1 is a longitudinal vertical sectional view of 65 my improved electric flat iron, parts of the handle being shown in section to disclose certain switches therein, the wiring being omitted for the sake of clearness; Fig. 2 is a view similar to Fig. 1 showing a modified 70 form of flat iron construction; Fig. 3 is a diagrammatic view of the wiring employed in the form of flat iron shown in Fig. 1, showing the switches in one position; Fig. 4 is a view similar to that of Fig. 3 showing 75 the switches in reversed position; and Fig. 5 is a diagrammatic view of the wiring used in connection with the form of flat iron shown in Fig. 2.

Corresponding and like parts are referred 80 to in the following description and indicated in all the views of the accompanying drawings by the same reference characters.

That form of my invention shown in Fig. 1 includes a flat iron body 10 formed of iron 85 and provided in its lower face with a relatively deep channel or groove 11 closely following the contour of the iron and providing a centrally disposed downwardly directed core 12. About this core are disposed 90 the electro-magnet coils 13, 14 and 15, all of these coils being wound in the same direction about the core, as shown in Figs. 3 and 4, and each being independent of the others and each formed from some suitable metal 95 of high resistance such as German silver wire or the like in order that they may not only act, in conjunction with the core 12 to form the electro-magnet, but also as heating coils for the flat iron. The terminals of 100 these coils pass outwardly through an opening 16 formed in the rear portion of the flat iron body 10. The coils are held in position within the channel 11 by means of a face plate 17 which covers the entire bottom of 105 the flat iron body, forming in effect the working face of the iron. This plate is constructed of aluminum or some other suitable nonmagnetic metal in order to in no way interfere with the action of the electro- 110

2
magnet. The face plate may be secured in any suitable manner as by the use of screws 18, it of course being understood that when such screws are employed the heads are 5 countersunk in the outer face of the face plate to lie flush therewith.

The flat iron is provided with a handle 19 of nonconductive material supported by shanks 20 and 21, the latter being formed 10 in two parts 22 and 23 which are secured to each other for relative movement by a screw 24 and nut 25, the screw 24 being passed through a slot 26 formed in the shank member 22. By this means the rear end of 15 the handle 19 may be raised or lowered at will and when suitably adjusted secured in place by tightening of the nut 25.

A bracket 27 carried by the rear portion 20 of the flat iron body 10 and insulated therefrom by a strip of rubber, fiber or other suitable insulating material 28, carries a knife blade contact 29, this being secured to the bracket by a screw bolt 30 which also serves as a binding post for connection to 25 one of the line wires. The shank member 22 carries a second bracket 31 which is insulated from the shank member by a strip of insulating material 32 and this bracket is provided with a knife blade switch 33 adapted 30 to engage between the parts of the knife blade contact 29 when the rear end of the handle 19 is in lowered position. The screw 34 securing this knife blade switch to its bracket also serves as a binding post.

35 The handle 19 is provided at its forward end with a pair of recesses 35 each of which is covered by a face plate 36 having a longitudinally extending slot 37. Positioned in these recesses are switches 38 and 39. Each 40 of these switches includes a pair of spaced apart, longitudinally extending contact blades 40 connected intermediate their length by a strip of insulating material 41 carrying a stud 42, also of insulating material, which extends through the slot 37 to 45 permit reciprocation of the switch member in the recess, the switch member and stud being so proportioned that the engagement of the reduced neck portion of the stud in 50 the slot holds the switch member in engagement against the bottom face of the recess. Positioned at the forward end of each recess are a pair of spaced contacts 43 and at the 55 rear end spaced contacts 44, while in each instance between the front and rear contacts there is positioned a second pair of contacts 45.

Having thus described the mechanical features of construction of my flat iron I will 60 now describe the manner of wiring the same, particular reference being had to Figs. 3 and 4 of the drawings. The line wire 46 and 47 are connected one to the binding post 34 of the switch blade 33 and the other to one 65 of the contacts 44 of the switch 38. Wires

48 and 49 connect diagonally disposed contacts 43 and 44 of the switch 38, while wires 50 and 51 connect diagonally disposed contacts 43 and 44 of the switch 30. A wire 52 connects that contact 44 of the switch 38 70 opposite the contact connected to the wire 47 with the adjacent contact 44 of the switch 39. One terminal of the magnet coil 13 is connected by a wire 53 to the binding post 30 of the switch blade contact 29 and the opposite terminal of said coil is connected by a wire 54 to the free contact 44 of the switch 39. That terminal of the magnet coil 14 corresponding to the first mentioned terminal of the coil 13 is connected by a wire 80 55 to one of the contacts 45 of the switch 39, while the opposite terminal of said coil is connected by a wire 56 to the other contact 45 of the switch 39. That terminal of the coil 15 corresponding to the first named terminals of the coils 13 and 14 is connected by a wire 57 to one of the contacts 45 of the switch 38, while a wire 58 connects the other of said contacts 45 of the switch 38 with the opposite terminal of the coil 15. 90

As previously set forth, the flat iron when in use, is employed in connection with an ironing board or table either formed of some metal having magnetic properties such as iron, or else formed with a plate or sheet of 95 such metal upon its upper face or inserted therein. Such a plate is conventionally shown at 59.

In operation the shank members 22 and 23 are so secured as to close the circuit between the switch blade 33 and switch contact 29 under which circumstances the current will pass through the wire 46, wire 53, coil 13, wire 54, one of the contact members 40 of the switch 39, wire 55, coil 14, wire 56, the 100 other contact member 40 of the switch 39, wire 52, one of the contact members 40 of the switch 38, wire 57, coil 15, wire 58, the other contact member 40 of the switch 38, and back through the line wire 47. It will 105 therefore be seen that the current will be in the same direction through all the coils 13, 14 and 15, thus both heating the iron and energizing the magnet. When the iron has become sufficiently heated, the article to be 110 ironed is positioned over the plate 59 and the iron then employed in the usual manner. The electro-magnet contained in the body of the iron, being energized, strongly attracts the plate 59 and therefore causes the iron to 115 exert a great pressure upon the garment being ironed. For this reason the iron itself may be constructed in such a manner as to be 120 relatively light and at the same time may be employed to exert great pressure upon a 125 garment being ironed without any effort on the part of the person using the iron. It will be clear, however, that at times such pressure would be too great, particularly when the iron was being used in connection 130

with laces or other delicate fabrics and for this reason I have provided the switches 38 and 39. Under such circumstances the position of both of these switches is reversed as shown in Fig. 4. It is hardly necessary at this point to trace the entire circuit now formed as it may be readily followed without such description. It is only necessary therefore to state that when the switches are set the current passes through the coils 13 and 15 in the same direction as before but through the coil 14 in reverse direction. Because of this the magnetic action will be greatly decreased as the magnetic action of one of the coils will be acting against that of the others and the total magnetic action will be that of one coil alone or one-third the usual action. At the same time inasmuch as the current passes through all the coils the heating effect will in no way be diminished. The relative magnetic effect may of course be varied in different irons by varying the number of coils and by providing additional switches similar to the switches 38 and 39.

In some instances it will be found that an electric iron is desirable in which the heating is accomplished either wholly or in part by coils entirely independent of the electro-magnet coils. For that reason there is illustrated a slightly modified form of the flat iron in Figs. 2 and 5 of the drawings.

Referring to Fig. 2 of the drawings, it will be seen that the body of the flat iron includes a hollow shell 60 of any suitable or desired shape and size, closed at its lower end by a face plate 61 similar to the face plate 12 and secured in the same manner. Mounted within the upper portion of this shell is a lining 62 of non-heat conductive material such as asbestos or the like and within this lining, which serves to protect the top of the shell 60 from heat, are heating coils 63, 64 and 65, these coils being connected in series with each other with the free terminals of the coils extending through perforations 66 and 67 formed in the rear portion of the wall of the shell 60. Seated within the shell 60 and immediately below these heating coils, and resting by its lower face against the plate 61, is a relatively thick plate 68 of iron, this plate being secured in place by screws 69 and being provided in its lower face with an endless channel or groove 70 corresponding to the channel 11 of the iron shown in Fig. 1. The magnetic coils 71, 72, and 73 corresponding to the coils 13, 14 and 15 are seated in this channel and their terminals passed through an opening 74 formed in the shell 60.

The flat iron is provided with a handle 75 supported by shanks 76 and 77 corresponding with the similar parts of the flat iron shown in Fig. 1, the handle being provided with switches 78 and 79 corresponding to the switches 38 and 39. The shank 77 car-

ries a switch blade 80 corresponding to the switch blade 33 and the flat iron has a bracket 81 corresponding to the bracket 27 but carrying a pair of oppositely disposed, spaced apart knife contacts 82 and 83 insulated from each other by a block 84 of rubber or other suitable material. As clearly shown in the drawings the switch blade 80 is so proportioned that it may engage both the contacts 82 and 83 at once when in central position or may be moved to engage either one separately as preferred.

The wiring of this form of flat iron is identical with that previously described with the exception of the following addition: One terminal of the heating coils is connected by a wire 85 to the contact 83 and its opposite terminal connected by a wire 86 to that contact 43 of the switch 78 which is connected to that contact 44 of the same switch from which the line wire 47 leads.

The operation of this form of flat iron is identical with that previously described if the knife blade 80 is positioned in such a manner as to engage only the contact 82. If, however, the knife blade 80 is moved to engage only the contact 83 the current will pass from the line wire 46, through the wire 85, heating coils, wire 86, wire 48 and back to the line wire 47, thereby heating the iron but in no way energizing the magnet. On the other hand, if the switch blade 80 is positioned to electrically engage both the contacts 82 and 83 the current will pass from the line wire 46 through the above described circuit and also through one or the other of the circuits described in connection with the form of iron shown in Fig. 1, which of these latter circuits the current will pass through being dependent upon the position of the switches 78 and 79. It will therefore be seen that with this form of flat iron the iron may be heated without any resultant magnetic action, that the iron may be employed in identically the same manner as the form of iron first described, and with the heating coils inactive and further that the iron may be employed with all the heating coils and all the magnetic coils in circuit, all the magnetic coils acting to energize the magnet or with both sets of coils in circuit but with one of the magnet coils active against the other to decrease the magnetic effect of the iron. Because of this construction a relatively light flat iron may be employed with practically little effort and the same results obtained as would be obtained by the employment of a very heavy flat iron of the usual type, as the greatest labor in ironing, of course, consists in the force required to press down upon the iron if it is light, or to raise and lower same out of position if it is heavy.

It will of course be understood that I do not wish to in any way limit myself to the specific details of construction illus-

trated in the drawings and described in the specification, as various minor changes, within the scope of the appended claims, may be made at any time, without in the 5 slightest degree departing from the spirit of my invention.

Having thus described the invention, what is claimed as new is:

1. A flat iron including a shell, electric heating coils in the shell, an electro-magnet in the shell, and means for supplying current to the coils and magnet, the supply of current to the heating coils being independent of the supply of current to the magnet.
- 10 2. A flat iron including a hollow shell, a lining of refractory material, heating coils positioned in the shell, an iron closure for the shell provided with an endless channel, coils disposed in said channel and forming 15 with the closure an electro-magnet, and a face plate of non-magnetic material secured to the outer face of the closure.
- 20 3. A flat iron including a hollow shell, heating coils in the shell, an electro-magnet in the shell, a handle carried by the shell, and a double knife switch carried by the handle adapted for connection with the heating coils and with the electro-magnet and with a source of electrical energy.
- 25 35 4. A flat iron including a shell, heating coils in the shell, an electro-magnet in the shell, a handle carried by the shell, and a double knife switch carried by the handle adapted for connection with the heating coils and with the electro-magnet and with a source of electrical energy, said handle being adjustable to selectively open and close the switch.
- 40 5. A flat iron including a hollow shell closed at its lower end by a face plate of nonmagnetic material, a plurality of heating coils in said shell, a core in said shell, and a plurality of magnet forming coils about said core.
- 45 6. A flat iron including a hollow shell closed at its lower end by a nonmagnetic face plate, a heating coil in said shell, a core in said shell, a plurality of coils wound about the core and forming heating coils and with the core forming an electro-magnet, and means for simultaneously passing a current through all the coils.
- 50 7. A flat iron including a hollow shell closed at its lower end by a nonmagnetic face plate, a heating coil in said shell, a core in said shell, a plurality of coils wound about the core and forming heating coils and with the core forming an electro-magnet, and means for selectively passing a current through either the first mentioned heating coil or through the coils about the core.
- 55 8. A flat iron including a hollow shell closed at its lower end by a nonmagnetic face plate, a heating coil in said shell, a core in said shell, a plurality of coils wound about the core and forming heating coils and with the core forming an electro-magnet, means for selectively passing a current through either the first named heating coil or through the coils about the core, and means for passing current through all of said coils.
- 60 9. A flat iron including a hollow shell closed at its lower end by a nonmagnetic face plate, a heating coil in said shell, a core in said shell, a plurality of coils wound about the core and forming heating coils and with the core forming an electro-magnet, means for selectively passing a current through either the first named coil or through the coils about the core, means for passing current through all of said coils, and means for reversing the direction of flow of current through certain of the coils wound about the core.
- 65 80 85 10. In testimony whereof, I affix my signature in presence of two witnesses.
